AIRPLANE ENGINE TEST CELL AND
LIGHTING THEREFOR

Davis H. Tuck, Redding Ridge, Conn., assignor
to Holophane Company, Inc., New York, N. Y.,
a corporation of Delaware

Application February 1, 1944, Serial No. 520,626

4 Claims. (Cl. 73—116)

1

The present invention relates to airplane engine test cells and lighting therefor.

The testing of airplane engines, airplane propellers, fuels and lubricants for airplane engines is carried out in test cells. Such cells must be large enough to receive the engine and propeller, or dynamometer, and handle the air impelled by the propeller or blown in for cooling, and they must be extremely strong and rigid to withstand the vibration set up during tests and afford protection. The engine is controlled from an observation station outside the cell proper, and in order to observe operations of the engine and accessories (except those requiring darkness) it is necessary to have available and to maintain throughout the test a relatively high level of illumination preferably in controlled directions. These test cells are usually monolithic concrete structures with heavy thick walls. The lighting equipment is recessed into the concrete so as to be flush with the wall surface.

It has been found that inbuilt lighting equipment of the ordinary type (metal box and lamp and lens cover) is unsatisfactory for the purpose, particularly in test cells where the larger engines are operated. Such an engine vibrates a test cell and everything connected with it to such an extent as to break lamp filaments and lamp mountings in the ordinary type of equipment so that it cannot be depended upon. As the lighting equipment is inaccessible when the engine is running, no repairs or replacements may be made without stopping the run.

The present invention contemplates discarding the usual metal box which supports the lamp (and reflector), as well as the light transmitting cover and utilizing the concrete itself as the means for supporting the lamp (and reflector), and means for supporting the cover whereby independent vibration of either the light source or the cover is reduced to the least possible amount.

A further object of the present invention is to provide suitable cover supporting means and lamp supporting means and preassemble them together with destructible concrete forms (adapted to provide a recess) whereby the same may be located in place in the forms used for making the concrete structures. After the concrete has set all the forms are removed and suitable framed recesses are formed each having a lamp supporting bracket supported in the recess.

Other and further objects will hereinafter appear as the description proceeds.

The accompanying drawings show, for purposes of illustrating the present invention, an

2

embodiment in which the invention may take form, it being understood that the drawings are illustrative of the invention rather than limiting the same.

5. In these drawings:

Figure 1 is a perspective view of an airplane engine test cell illustrating the disposition of lighting equipment in it;

Figure 1a is an end view of the same;

10. Figure 2 is an elevational view taken in the direction of the arrow 2 of Figure 1, showing the reinforcing member or ring, the frangible box and the lamp supporting bracket, conduit pipes and air pipe all secured to the form, and before the concrete is poured;

15. Figure 3 is a fragmentary elevational view of the reinforcing ring or member taken from the left of Figure 2;

20. Figure 4 is a fragmentary elevational view of the same taken from the right of Figure 2, the concrete form being omitted;

Figure 5 is a side elevational view of the wooden form or box carried by the ring of Figures 3 and 4;

25. Figures 6a and 6b are elevational views of different forms of anchor or mounting bracket for the lamp support;

Figure 7 is a vertical sectional view through a complete luminaire;

30. Figure 8 is an elevational view of the luminaire taken from the right of Figure 7; and

Figure 9 is a sectional view of the structure of Figure 7 taken on the line 9—9 of Figure 7.

35. A reinforced concrete test cell for airplane engines is illustrated in an outline in Figures 1 and 1a. It is generally an L-shaped structure with a long horizontal base 10 and an upwardly extending intake 11. Near the middle of the horizontal portion 10 the test cell has a throat portion 12 of cylindrical contour. The intake duct 14 and exhaust duct 15 may be made square and are here shown as having their sides of the same length as the diameter of the cylindrical throat. The square portions and cylindrical portion are merged by sloping areas indicated at

40. 13, 14.

The walls of the test cell are from three to four feet thick and the diameter of the throat may be sixteen to twenty feet, this being sufficient to clear the propeller of the engine. The test cell is provided with a window indicated at

45. 16 which communicates with an observation station and operating room 17.

46. Provision is made for the lighting equipment during the building of the test cell. A suitable

arrangement of lighting equipment is illustrated in the drawing, according to which luminaires 18, 18 are placed in the roof of the cell on either side of the throat and other luminaires 19, 19 are placed in the concrete structure at the throat portion.

Reference is now made to Figures 2 to 6, inclusive. The form used for providing the inner surface of the test cell is indicated at 20. A cast iron, ring-like, reinforcing member 21 has a smooth outwardly flanged front face 22 and a rearwardly extending flange 23. At the corners the flange 23 is made deeper, as indicated at 24, and the inner end of these corner portions is flanged outwardly, as indicated at 25. Each of the four sides of the front face of the ring-like member 21 is provided with recesses 26 from which project forwardly extending bolts 27 supported on pins 28.

A five-sided wooden box is illustrated separately in Figure 5. This box is just the right size so that its side walls 29a will fit inside the rearwardly extending flanges 23 of the ring-like member 21, and the box is secured to the metal ring by screws indicated at 30. The open end of the box is kept from collapsing by crossed braces 29b and 29c. The back 29d of the wooden box carries a cast iron or steel bracket or anchor such as the anchor 31 arranged for mounting in the side of the box or the anchor arranged for mounting in the back of the box. The type of anchor used is dependent on the way the concrete is poured. The bracket and wooden box may be fastened together in any suitable manner so that the bracket has a definite and fixed location relative to the cast iron ring 21, and the box is constructed in parts to facilitate renewal.

The ring 21, the box 29 and anchor 32 are pre-assembled and shipped to the place of installation. The wooden walls of the box are drilled at suitable places to receive conduit pipes indicated at 33, 33.

When the preassembled structure including the mounting bracket, the box and the anchor is to be mounted in the forms used for pouring the concrete in building the cell, holes are drilled through the wooden form according to a templet so that the bolts 27 can be passed through the holes in the form and the parts all bolted together, as indicated in Figure 2. Similar provisions will be made for all of the luminaires with which the test cell is to be equipped, and all these parts will be in place before the concrete is poured. When the concrete is poured a monolithic structure will be formed wherein the cast iron ring 21, the anchorage member 30, and the pipes 33 are all permanently secured in place. After the main forms have been removed it is possible to break out the boards forming the wooden box 29 so that the recess is formed in the reinforced concrete, this recess being framed by the reinforcing member 21 and carrying the bracket 31 or 32 projecting inwardly and at the same time the piping is available.

Referring to Figures 7, 8 and 9, the anchor or bracket 31 or 32 is used to support a socket supporting strap 35 which is held in place by bolts indicated at 36. This strap has a forwardly extending portion 37 adapted to support a lamp socket 38 and a rearwardly extending portion 39 adapted to support a reflector 40. Variously dimensioned straps 35 may be employed with various locations of holes for mounting purposes so that the position of the light center LC of the incandescent lamp 41 may be located to have

a desired offset. It will thus be seen that the vibrations which can be communicated to the lamp are minimized. They are much less than would be the case where there was a direct connection to the lamp support as in the case of the common metal box.

The bolts 27 are employed to clamp a plate 42 against the flange 22, a gasket 43 being employed to insure a tight joint. The plate 42 is provided with a rectangular opening 44, and across this opening is a tempered glass plate 45 and a prismatic glass plate 46. These plates are clamped in place by clamps indicated at 47. These plates are preferably set in an elastic cement 48 which does not harden.

The lens 46 is one designed to operate with the lamp and reflector and give a predetermined distribution of light which can be varied by varying the offsetting of the lamp as indicated by dot-and-dash lines in Figures 7 and 9. The offsetting for the luminaires is dependent upon the position in the set up and where the light is to be directed. The luminaires in the throat portion are generally arranged to direct the light leftwardly, as indicated in the drawings, so as to illuminate the propeller end of the engine, while the luminaires in the roof of the intake and exhaust ducts are similarly arranged to concentrate the light output on to the engine. The lighting equipment on the side of the throat opposite the observation window will generally be employed only during setting up operations and will be turned out when the engine is running, in order that all the light will come from the same side of the engine as the observation station. The lighting equipment is flush with the surface of the concrete and presents minimum obstructions to the flow of air. It has smooth surfaces on which there is the least tendency for the accumulation of oil, and the oil is kept off the lens so that there is a minimum interference with light control.

Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

50 What is claimed is:

1. A test cell for airplane engines comprising a monolithic concrete structure with horizontally extending inlet and exhaust ducts and an intermediate throat portion of circular cross section, the top of the inlet and outlet ducts and the periphery of the throat portion having inwardly opening recesses each provided with a reinforcing ring-like frame partly embedded in the concrete to be flush with the surface thereof, a flat cover frame carrying a light transmitting plate clamped against the reinforcing frame to form a closure for the recess, a bracket member anchored in the concrete in each recess independently of the ring-like member, and a light source secured on each bracket.

2. In a vibration resistant test cell for aviation engines and the like, a monolithic concrete structure having an inwardly opening recess provided with a reinforcing ring-like member partially embedded in the concrete, a bracket member anchored in the concrete independently of the ring-like member and accessible in the recess, a light source and reflector secured to the bracket, an exposed apertured frame secured to the ring-

like member, and a light transmitting plate secured to the frame.

3. In combination, a monolithic concrete structure having a recess, a bracket having an anchorage portion cast into the wall and a mounting portion extending into the recess, a ring-like frame independent of the bracket and having anchorage portions cast into the wall and exposed portions forming the framing of the mouth of the recess, a light source, means for securing the light source to the mounting portion of the bracket and disposed in the recess, a second frame carried by the first frame, and a light transmitter carried by the second frame, the transmitter and second frame closing off the recess.

4. A system of lighting for a horizontally extending, airplane engine test cell having a cylindrical throat portion adapted to receive the propeller, an intake duct to supply air, and an exhaust duct adapted to receive the engine, said cell being a monolithic concrete structure, comprising luminaires disposed along the throat portion and adjacent portions of the ducts, each luminaire including a mounting plate cast into the concrete structure about the periphery of an inwardly opening recess to form a framed opening about the recess and substantially flush with the inner surface of the concrete structure, a light-concentrating lens plate carried by the mounting plate and normally fixed in position to be flush with the mounting plate, a mounting bracket independent of the mounting plate and cast into the concrete structure at the inner end of the recess so that the concrete forms the sole interconnection between the mounting plate and the bracket, and a lamp and reflector adjustably mounted on the bracket whereby the direction of

the beam emitted from the lens plate may be projected in selected directions and the directions of all the beams may be varied to afford different illumination patterns, without varying the normal positions of the lens plates.
